B. C. RUSSELL.

GATE HINGE.

APPLICATION FILED NOV. 9, 1911.

Patented July 16, 1912.

UNITED STATES PATENT OFFICE.

BURTON C. RUSSELL, OF KEENE, NEW HAMPSHIRE.

GATE-HINGE.

1,032,776.

Specification of Letters Patent. Patented July 16, 1912.

Application filed November 9, 1911. Serial No. 659,337.

To all whom it may concern:

Be it known that I, BURTON C. RUSSELL, residing at Keene, in the county of Cheshire and State of New Hampshire, have invented certain new and useful Improvements in Gate-Hinges, of which the following is a specification.

This invention, which generally relates to gate hinges, more particularly has reference to hinges for self-closing gates in which an inclined trackway or bearing is provided for returning the gate to the closed position when released, after being manually opened, and the said invention primarily has for its object to provide an improved hinge for a gate of the character stated that is simple, can be economically made, easily manipulated and which effectively serves its intended purposes.

20 My invention consists of a hinge embodying the peculiar construction and novel arrangement of parts hereinafter fully described and specifically set out in the appended claim and illustrated in the drawing, 25 in which:—

Figure 1 is a side elevation of so much of a self-closing farm gate as is necessary to illustrate the practical application of my said invention. Fig. 2 is a perspective view 30 of the bracket member or fixedly held bearing portion of my improved hinge construction. Fig. 3 is a vertical cross section of the parts as shown in Fig. 4, and Fig. 4 is a plan view of the parts shown in Fig. 3, the 35 hinge post being shown in section.

In the drawing, I have shown so much of a self-opening farm gate as is necessary to illustrate the practical application of my invention, and in the said showing, 12 designates the rear bar of the gate, 5 the hinge post and 3 a strap iron bolted to the upper end of the gate bar 12 and which has an outwardly projected apertured member 30, for pivotally engaging with the upper 40 hinge pintle 4, integrally formed with the upper hinge bracket 40 that is secured upon the upper end of the hinge post 5.

13 designates the lower hinge and bearing portion of my improved hinge construction upon which the lower end of the gate is mounted and which forms, as it were, a bearing bracket for the lower or fulcrum bearing for the gate. The bracket 13 is a substantially U-shape member whose opposite arms 13^a—13^a are bent upwardly upon

a sharp incline so as to form the runway for the roller or fulcrum bearing 14 presently again referred to, and the said arms 13^a have portions bent at right angles to the central portion of the bearing 13 to form 60 straps 13^b, which are apertured for receiving the bolts that connect with the post 5. The bearing 13 also includes a flat central horizontal extension 13^c provided with a central aperture 13^d, and the rear portion of 65 the extension 13^c is rolled or otherwise formed into a long bolt 13^e for passing through the post 5, the end of the bolt being threaded to receive nuts 13^f (see Fig. 3).

15 designates the lower hinge pintle that 70 is formed by bending a plate 16 to the desired shape and with a foot portion 15^a that is provided with an aperture to receive a fastening bolt for securing it to the post 5.

The fulcrum bearing 14 hereinbefore referred to is in the nature of a roller bearing, and it is journaled in a keeper plate 18 that is integral with and forms the rear end of a bifurcated strap member 19, which embraces the lower gate rail or bar, and is 80 bolted thereto as shown.

From the foregoing description taken in connection with the drawings, the complete construction, the manner in which my gate may be manipulated and its advantages will 85 be apparent.

It will be noticed, that when provided with my hinge construction it is not necessary to dismount to open the gate, since in swinging the gate in either direction the 90 lower or fulcrum bearing 14 of the gate hinge will ride up on the incline portions of the bearing bracket 13 and when pressure on the gate is released, the said fulcrum bearing 14 will readily swing back 95 down the incline portions 14 to the closed position.

What I claim is:

A gate hinge of the character described comprising a body of strap iron including 100 a U-shaped portion, the opposite members of which are curved upwardly to form inclined bracket bearings, and then bent perpendicularly with respect to the bracket bearings to form portions for attaching to 105 the hinge post, the said body also including a horizontally extended member that terminates in a threaded bolt shank for passing transversely through the posts, said horizontal member having an aperture and 110

a member secured to the post having a pintle that extends up through the aperture in the horizontal member of the U-shaped body to form a pintle, and a roller bearing for engaging the inclined bracket portions of the U-shaped member, said roller bearing having an apertured ear for engaging the

pintle, the said roller bearing also having portions for connecting with the lower end of the gate.

BURTON C. RUSSELL.
